RICHARD WILHELM TERLINDEN, OF JYVASKYLA, FINLAND, ASSIGNOR TO WILH. SCHAUMANS TARSO AKTIEBOLAG, OF JYVASKYLA, FINLAND.

METHOD FOR PRODUCING IMITATIONS OF VALUABLE WOODS AND INLAID WORK ON WOOD BY THE AID OF TRANSFER WORK.

Application filed January 19, 1923. Serial No. 613,771.

To all whom it may concern:

Be it known that I, RICHARD WILHELM TERLINDEN, citizen of Germany, residing at Jyvaskyla, Finland, have invented certain new and useful Improvements in a Method for Producing Imitations of Valuable Woods and Inlaid Work on Wood by the Aid of Transfer Work, of which the following is a specification, for which I have filed an application in Germany on December 19, 1921.

The methods for imitating valuable woods, and for making inlaid work on less valuable woods, as used heretofore, in so far as they are based on bodily transferring pictures and designs, and in so far as they do not deal with the mere imitation of woodstreaks, have made use of transfer pictures of comparatively small dimensions, in which the colours are applied to an opaque layer (leaf-metal, white body colour or the like). The necessity for such an opaque layer was due to the fact that large surfaces could not be mechanically transferred in a simple manner and with certainty of success. One was confined to imitating small inlaid work, but could not imitate relatively large panels. Panels were usually first provided by hand, and over the whole surface, with the necessary wood tone (for instance chestnut wood, walnut wood or the like), and then on the surface thus painted or stained, the comparatively small pictures were transferred.

The present invention now permits mechanically covering large surfaces with a unitary transfer picture, and thus produces an imitation which cannot be distinguished from the natural wood. This is accomplished by transferring the transfer picture, without any ground layer (such as leaf-metal, white body colour or the like) directly on a previously roughened wood surface by means of pressure and heat.

The new method differentiates from the old methods, in that pressure and heat is applied. It has been proposed to make use of ordinary printed paper, the colour layer of which has been applied under pressure and heat, to the raw wood. However this method has the drawback that the paper holds back those parts of the colour which have been absorbed by the paper fibers, and therefore the picture on the wood will always appear pale.

Another difference over the known

methods consists in first roughening the wood. Heretofore the primary necessity for transferring transfer work on wood was a wood surface smoothened by a ground lacquer surface or by polish. However, when the wood is thus smoothened in any manner there is the defect that the colour layer transferred will be easily damaged in use together with the delicate lacquer layer, or that it will scale off and become cracked.

According to the present invention the roughening of the wood is preferably carried out by means of a solution of one part of shellac and 10 parts of spirit. In this solution the spirit has as object to raise the fibers of the wood, while the shellac has as object to retain the wood surface in this raised condition until the transferring by heat and pressure has been effected. Due to the heat the shellac is liquefied and penetrates the pores of the wood, and therefore does not remain as a layer on the wood surface. Due to the pressure during the heating, the wood fibers which had been raised by the spirit to facilitate the transfer will be pressed down smooth.

The complete process brings out another very important advantage which allows the production of natural imitation. Since the body or opaque layer is missing transfer designs can be produced which can be made transparent at those places which, in the finished work correspond to the natural tone of the wood. This is done, for instance, in producing transfer designs by the known photographic autotyping, by excluding, on the colour plate, such desired tones as are present in the wood onto which the transfer is to take place. In this case all soft and light tones will be printed with transparent colour. In this manner very finished imitations of valuable woods can be produced by thus partly exposing the natural wood of the foundation, and allowing it to shine through.

By effecting in the above manner, a decided and complete separation of the colour layer from the transfer paper, and obtaining its penetration of the wood foundation, there is obviated all those difficulties which stand in the way of transferring of unitary transfer work onto large surfaces.

Heretofore great difficulty has been met with, in printing from printing plates (for instance lithographic stones) on which the

originals are produced by photographic autotype on transfer paper, since the usual gum- or dextrin-layer repels the printing colour. Further, for instance in the 5 lithographic press, the amount of adhesive given off by the transfer paper to the moistened stone will by degrees spoil the drawing and smut the fine lines or spots produced by the screen or grid. All these drawbacks are 10 naturally greater the larger the transfer pictures are. To avoid these drawbacks, it has been proposed, it is true, to coat the soluble layer with a chromo-layer. This, however, besides being a very difficult manipulation, has the drawback that the chromo-layer, after the pulling off has been carried out, covers the picture and must be washed off, whereby the colour layer may be easily 15 damaged. By a further feature of the 20 present invention the above named drawbacks are obviated by varnishing the transfer paper once or twice, for instance in a lithographic press, over its complete surface. By these means, it is assured that the colour 25 will be printed without blemish, and at the same time that the transferring of parts of the soluble layer of the paper (gum, dextrine or the like) onto the stones, is prevented. The paper thus prepared is printed 30 in the usual manner. This gives a further advantage, in that the transfer paper thus prepared with varnish will be subject to action of the air temperature and humidity to a much less degree than otherwise, and 35 therefore will not warp, so that the various colours will remain in their desired correct grouping, and without any distortion. The necessary heat for transferring the picture on wood, when the paper is prepared in the 40 said manner, can be reduced to a minimum.

Finally the size of the transfer pictures makes it necessary to prevent all tendency to blister. This tendency is obviated, according to the present invention, in a mechanical way. Transfer methods heretofore known were either completely unsuitable for mechanical production or for production on a large scale, as being too complicated, or as unfitted to cover large surfaces, on account of the formation of blisters.

In the drawing, by way of example, a press is shown by the aid of which the formation of blisters or creases of the transfer paper is avoided with great certainty. The 55 operation of this press is carried out by pressure applied in any desired manner.

Fig. 1 of the drawing is an elevation of an upper press plate;

Fig. 2 is an elevation of an under press 60 plate;

Figs. 3 and 4 show side views of the plates.

In the center of the lateral edges of the heated upper press plate *a*, bolts *b* and *c* are fastened. Below the press plate *a* a springy 65 metal plate *d*, bent downwardly, is arranged. In the center of the lateral edges of the plate *d* ferrules *e* and *f* are attached, which are adapted to slide on the bolts *b* and *c* and, bending upwardly from the plate *d*, present 70 displacement in a horizontal direction. When tensioned to a slight extent, the plate *d*, with its free outer ends, will bear against the lateral edges of the press plate *a*, and with its ferrules *e* and *f*, on the heads of 75 the bolts *b* and *c*. When the press material *p* (a wood plate with superposed paper) is shifted on to the lower table on closing the press, first a proper pressure will be exerted in the middle, and which expands toward the sides, the more the press surfaces approach each other. Thus the paper will be smoothly pressed onto the wood plate, starting from the center and working outwardly, without blisters or creases. 80 85

A number of suggestions have been made heretofore to prevent the formation of blisters, as by striking along the paper or by pressing it by atmospheric pressure. However, the above described press is a 90 decided advance, since the springy plate attached to the machine requires no special manipulation, and at the same time allows the application of heat and pressure according to the above described method, for 95 any length of time.

In practice it has been found that a pressure of 5 kg. to 1 □ cm. and a temperature of 110° C. will be amply sufficient.

I claim:

1. A method for producing imitations of valuable woods and inlaid work on wood, by means of bodily picture transfer work, comprising, roughening the wood surface, and transferring the picture directly onto 105 the roughened wood surface, under application of pressure and heat.

2. A method for producing imitations of valuable woods and inlaid work on wood, by means of bodily picture transfer work, comprising producing a transfer picture which is transparent at those places the tones of which correspond with the tones of the natural wood color, roughening the wood surface, and transferring the picture directly onto the roughened wood surface under application of pressure and heat. 110 115

3. A method for producing imitations of valuable woods and inlaid work on wood, by means of bodily picture transfer work, comprising roughening the wood surface by means of a solution of shellac in spirit, and then effecting the transfer.

RICHARD WILHELM TERLINDEN.
